United States Patent Office.

J. S. MERCHANT, OF HOPE DALE, OHIO.

Letters Patent No. 97,791, dated December 14, 1869.

IMPROVED WASHING-MACHINE.

The Schedule referred to in these Letters Patent and making part of the same

To all whom it may concern:

Be it known that I, J. S. MERCHANT, of Hopedale, in the county of Harrison, and State of Ohio, have invented a new and useful Improvement in Washing-Machines; and I do hereby declare that the following is a full, clear, and exact description thereof, which will enable others skilled in the art to make and use the same, reference being had to the accompanying drawings, forming part of this specification.

This invention relates to a new and useful improvement in machines for washing clothes, and consists in the construction and arrangement hereinafter described.

In the accompanying drawing—

Figure 1 represents a longitudinal vertical section of the machine.

Figure 2 is a top view.

Similar letters of reference indicate corresponding parts.

A is the box or vessel, which is of oblong form and suitable depth, and elevated on legs B.

C is the bed, or concave, in two parts, together forming the arc of a circle, of corrugated surface.

Each portion of the concave is kept in position by means of the end-pieces D, to which the corrugated bed C is fastened, which pieces extend back to the ends of the machine or box, as seen in the drawing.

E is the rubber, which is semicircular in form, with a ribbed surface.

This rubber forms the end of a lever, whose fulcrum is at F, and the machine is operated by oscillating this rubber, by means of the lever, back and forth over the concave, the clothes to be washed being placed between the two.

G is the fulcrum-rod, the end of which enters slots

H in the sides of the machine-box A, which slots allow the fulcrum-pivots F and rubber to rise and fall, according to the quantity of clothes in the machine.

The two parts of the concave C are readily removable from the box.

By removing one part, the machine is adapted to washing bed-quilts or other heavy articles. When both parts are employed, as seen in the drawing, the machine is ready for finer articles, or for ordinary washing.

It will be seen that the rubber rests on the clothes, and that the air is expelled by a squeezing and rubbing-process, which proves more effective than any other in washing clothes.

The spaces J J, between the end-pieces D, behind the ends of the concave, allow sufficient space for soaking the clothes before washing, thus rendering the common wash-tub unnecessary for the purpose.

The rubber is readily lifted from the machine by the lever K, when that is necessary.

Having thus described my invention, What I claim as new, and desire to secure by Letters Patent, is—

The washing-machine, consisting of the rectangular tub A, the removable concaves C C, provided with end-pieces or extensions D D, forming the spaces J J, and the semicircular rubber E, forming one end of a lever; K, whose fulcrum-rod G works in vertical slots in the sides of the tub, all constructed, combined, and arranged as shown and described.

J. S. MERCHANT.
